(57) **CLAIM**

The ornamental design for a syringe-to-syringe coupler, substantially as shown and described.

DESCRIPTION

FIG. 1 is a perspective view of a syringe-to-syringe coupler according to an embodiment of the design.

FIG. 2 is a front view of the syringe-to-syringe coupler shown in FIG. 1, the rear view being substantially identical to the front view.

FIG. 3 is a top view of the syringe-to-syringe coupler shown in FIG. 1, the bottom view being substantially identical to the front view.

FIG. 4 is a first (left or right) side view of the syringe-to-syringe coupler shown in FIG. 1, the opposite side view being substantially identical to the front view; and,

FIG. 5 is a perspective view showing the environment of a syringe-to-syringe coupler according to the design in use coupling two syringes.

Portions shown in broken lines are for illustrative purposes only and form no part of the claimed design.

1 Claim, 3 Drawing Sheets
